SEQUENTIALLY OPERATED MULTIPLE BLOWER

Edward Claude Shakespeare Clench, Leamington Spa, England, assignor to Automotive Products Company Limited, Leamington Spa, England

Application April 6, 1945, Serial No. 586,946
In Great Britain January 7, 1944

16 Claims. (Cl. 15—316)

1

This invention relates to sequentially operated multiple blowers and has especial reference to hydraulically operated soot blower systems for boiler and like furnaces. The principles involved are, however, applicable to sequentially operated multiple blower systems used for other purposes.

It is the object of the invention to provide an improved form and construction of motor device for use in systems where a plurality of such devices are fed from a common source of pressure liquid and are desired to operate one after another in a predetermined sequence, each motor device being of the kind (hereinafter mentioned as the kind referred to) incorporating a change-over valve which conducts the supply of pressure liquid to the motor proper when the device is actually operating and thereafter to a bypass connection leading to the supply inlet of the change-over valve belonging to the next motor device in the sequence.

In a hydraulic remote control system having a motor device of the kind referred to, according to the invention the change-over valve is resiliently influenced to assume a position in which the liquid passes from the supply connection to the bypass connection. Preferably holding means act upon the change-over valve to retain the latter in its feed position in which it places the supply connection in communication with the hydraulic motor of the device, said holding means being automatically released when said hydraulic motor has moved a predetermined amount. The holding means conveniently comprises a member which is moved by the hydraulic motor in a direction substantially at right angles to the direction of valve movement, said member being arranged so that after a predetermined movement it frees the valve and permits the latter to be moved to its bypass position by a spring constituting the said resilient influence.

According to a further feature of the invention there is provided for a soot-blower system, a hydraulically operated nozzle-actuating unit comprising nozzle-rotating mechanism, a hydraulic motor driving said mechanism, a change-over valve which latter receives pressure liquid from the supply and in one position feeds it to the hydraulic motor, and in another position delivers it to a bypass connection leaving the motor inoperative, spring means urging the selector valve to its bypassing position, means for moving the valve to its feed position, and holding means which retain said valve member in said feed position and are actuated by the motor to release the valve when the motor has moved a predeter-

2

mined amount, thus allowing the spring means to move the change-over valve to its bypassing position. If desired, integrating mechanism, operated at each revolution of the nozzle, may control the holding means and cause the change-over valve to be released when the nozzle has made a predetermined number of revolutions. This integrating mechanism can conveniently comprise a holding member which is slideable at right angles to the direction of valve movement, and ratchet mechanism actuated by, or in common with, the nozzle to move the said holding member, the latter being arranged to move to a position in which the change-over valve is freed when the nozzle has made a predetermined number of revolutions.

The improved form of motor unit is particularly suitable for operating the blower nozzles of soot blowers and the invention will therefore be described in this connection by way of example. Hydraulically operated soot blowers are, of course, well known and the nozzle devices fall into two classes, namely the non-retractable type and the retractable type. In the non-retractable type a nozzle fitted into the wall of the furnace is arranged, when operative, to inject steam or other cleaning fluid and at the same time merely rotate about its axis. On the other hand, in the retractable type of blower the nozzle is projected axially into the furnace immediately prior to the blowing operation and is then rotated while the blowing takes place, said nozzle subsequently being retracted to its original position, thus bringing the operation to a close.

35 The invention is illustrated by way of example in the accompanying drawings, in which:

Figure 1 is a fragmentary side elevation of a blower head of the retractable type, some of the internal parts being shown in dotted lines;

40 Figure 2 is a sectional elevation, drawn to an enlarged scale, showing the internal arrangement of the integrating mechanism and its associated valve device;

45 Figure 3 is a fragmentary sectional plan taken on the line III—III of Figure 2;

Figures 4, 5 and 6 are diagrammatic elevations showing parts of the integrating mechanism in various operative positions;

50 Figures 7 and 8 are views corresponding to Figure 3 and showing the masking plate in different positions, the sections being taken on the lines 7—7 and 8—8 respectively of Figures 4 and 5;

Figure 9 is a sectional elevation of a modified form of integrating mechanism and valve device

55

for use with a blower nozzle of the non-retractable type;

Figure 10 is a similar view of another construction of integrating mechanism and valve device for a non-retractable blower nozzle; and

Figure 11 is a fragmentary sectional plan taken on the line XI—XI of Figure 10.

The blower head shown diagrammatically in Figure 1 is of the retractable type and comprises a hollow body 10, through which extends a main shaft 11 carrying the blower nozzle indicated at 12. The main shaft 11 is formed with a pair of flanges 13 and 14, which are engaged by a fork member 15 pivoted to the body at 16. At its upper end the fork 15 has an arm 17 connected to the piston rod 18 of a double-acting hydraulic piston and cylinder motor indicated generally at 19, and shown more particularly in Figure 2. It has a piston 18' slideable in a cylinder 20, which latter is pivotally connected at 21 to the body 10; thus as the piston rod 18 is moved to the left the fork 15 acts as a lever, causing the main shaft 11 and nozzle 12 to slide axially to the right. The main shaft 11 and nozzle 12 are rotated by a hydraulic motor 22 of the rotary type having an output shaft 23 connected by a pinion 24 and countershaft gears 25, 26 with a gear wheel 27 mounted upon a driving sleeve 28, which is rotatable within the body 10, but is located against axial movement. The parts numbered 23 to 28 are shown in dotted lines in Figure 1. The main shaft 11 has a stem portion 29, which is axially slideable within the driving sleeve 28 but is connected therewith by splines or keys enabling a rotational drive to be imparted to the shaft 11 without impeding its axial movements. A cam 30 mounted upon the shaft 11 and rotating therewith actuates a valve 31 for steam or other cleaning fluid, through the medium of a tappet 32 and a rocker 33 pivoted to the body 10 at 34; the admission pipe for cleaning fluid is indicated at 35. Mounted upon the side of the body 10 is a valve device 36 arranged to produce the desired automatic actuation of the reciprocating motor 19 and the rotary motor 22, said valve device 36 being actuated by a holding device comprising control mechanism 37. For actuating this mechanism (which will be described in detail hereinafter) the piston rod 18 is connected by a link 38 with an arm 39, the spindle of which is indicated at 40, said spindle 40 thus being oscillated by the arm 39 as the blower nozzle 12 reciprocates. The gear wheel 27 is provided on its right hand face adjacent its periphery with a cam 41, which is adapted to push a tappet 42 towards the right, thus actuating an arm 43 and causing a spindle 44 to be oscillated, once for each revolution of the blower nozzle 12. The parts numbered 41 to 44 are shown in dotted lines in Figure 1.

The internal construction of the valve device 36 and also the integrating mechanism 37 are shown more clearly in Figure 2, which also indicates diagrammatically the connections to the various components of the external hydraulic control circuit.

The valve device 36 is formed with two mutually parallel bores 50 and 51 containing respectively a change-over piston valve member 52 and a selector valve member 53, the latter also being of the piston type. The piston valve member 52 is urged to the right by a coiled compression spring 54 when permitted by the holding device 37 and it has at its opposite end a cylindrical stem 55, which slides through a fluid-tight packing 56 and is of reduced diameter so as to form

an annular working space 57 within the bore 50. At its middle part the bore 50 has an enlarged space 58 communicating with a pressure liquid inlet connection 59, which latter is fed with pressure liquid from a pump 60 through the medium of a pipe 61, a control valve 62 and a pipe 63. The pump 60 is of course fed with liquid through a pipe 64 leading from a reservoir 65. The control valve 62 is also arranged to supply pressure liquid through a pipe 66 to a connection 67 leading into the annular working space 57; this operation is herein termed "re-setting," the pressure liquid acting upon the valve member 52 and forcing it to the left against the action of the coiled compression spring 54. A branch connection 66a leads to the next blower unit in the sequence and is of course joined to the connection 67 thereof. Only a single control valve 62 is required for the whole system, and is manually operated for starting the blowing operation, and for resetting all the integrating mechanisms. The change-over valve member 52 is formed with two circumferential grooves 68 and 69, which are respectively in permanent communication with ports 70 and 71 and which grooves 68 and 69 are adapted to communicate one at a time with the enlarged space 58, thus placing the latter in communication with the port 71 when the valve member 52 is in its left-hand position, as shown, and in communication with the port 70 when the valve member 52 is in its right-hand position. The port 70 leads to a bypass connection 73 comprising a pipe which leads to the inlet connection (corresponding to 59) of that blower which is to be operated next in the sequence, i. e. which is required to operate by pressure liquid from the pump 60, when the present blower has made a complete blowing operation. The port 71 is constituted by the end of a passage 74, the opposite end of the latter serving as a pressure inlet port 75 for the selector valve member 53. The piston valve member 53 has at its right-hand end a stem 76 of reduced diameter in order to provide an annular working space 77, which latter is connected with the annular working space 57 by a passage 78. The stem 76 slides through a fluid-tight packing 79 and the valve member 53 is urged to the right by a coiled compression spring 80 in a manner similar to the valve member 52 that is, when permitted by the holding device 37; thus both valve members are re-set (i. e. moved to the left) simultaneously whenever pressure liquid is fed to the connection 67.

The selector valve member 53 has a circumferential groove 81 which is in permanent communication with the pressure inlet port 75, and which serves to conduct pressure liquid through a radial passage 82, an axial passage 83, and radial passages 84 to a narrow circumferential groove 85 adjacent the left-hand end of the valve member 53. This valve member has three operative positions, and, as shown, it is in its left-hand position, the groove 85 being in register with a port 86 having a connection 87. In the central position of the valve member 53 the groove 85 registers with a port 88 leading to a connection 89; similarly when the valve member 53 is in its right-hand position the groove 85 communicates with a port 90 leading to a connection 91. The reservoir 65 is coupled by a pipe 92 with a drain connection 93; this connection 93 has a transverse passage 94 leading to the spaces 95 and 96 at the left-hand ends of the bores 50 and 51 respectively, while a passage 97 connects the reservoir permanently with a wide circumfer-

tial groove 98 formed in the valve member 53. It will be seen that when the groove 85 registers with any one of the three ports 86, 88 and 90, the other two ports are in free communication with the reservoir 65, either by way of the space 96 or the groove 98.

The connections 87 and 91 lead by pipes 99 and 100 respectively to the corresponding working spaces 101 and 102 of the reciprocating motor 19; also the connection 89 leads by a pipe 103 to the inlet of the rotary motor 22, the exhaust from the latter being returned through a pipe 104 to the reservoir 65.

The operation of the valve device 36 is briefly as follows. With the valve members 52 and 53 in their "re-set" positions the by-pass valve member 52 being in its feed position as shown in Figure 2, the control valve 62 is operated to deliver pressure liquid through the pipe 63 and thence by way of the groove 69 to the feed passage 74, groove 81, passages 82, 83, 84, and groove 85 of the valve member 53; the pressure liquid therefore flows by means of the port 86, connection 87 and pipe 99 into the working space 101 of the reciprocating motor 19 (see Fig. 2) and causes the blower nozzle 12 to be advanced into the furnace by the action of the piston 18', rod 18 and lever 15, the liquid expelled from the working space 102 flowing by means of a pipe 100 and connection 91 through the port 90 into the groove 98 and thence back to the reservoir 65 by way of the passages 97, 94, connection 93 and pipe 92. The advancing movement of the blower nozzle actuates the integrating mechanism 37, as will be hereinafter explained, thus causing the valve member 53 to assume its central position with the groove 85 in register with the port 88. This causes the pressure liquid to be fed from the groove 85 through port 88, connection 89 and pipe 103 to the rotary motor 22 so that the blower nozzle 12 is continuously rotated while it is in its advanced position. This rotation also actuates the integrating mechanism 37, as will be hereinafter explained, and after a predetermined number of revolutions, causes the valve member 53 to assume its right-hand position, the groove 85 then being in register with the port 90 so that pressure liquid is fed through the pipe 100 to the working space 102 of the motor 19. This brings about retraction of the blower nozzle 12, and at the completion of this movement the integrating mechanism 37 frees the change-over valve member 52, thus enabling the latter to slide to its right-hand by-passing position under the action of the coiled spring 54. In its new position the groove 68 of the valve member 52 bypasses the pressure liquid from the connection 59, to the port 70 and the by-pass connection 73 leading to the next blower unit in the sequence; the groove 69 is, of course, isolated from the port 59 when the valve member 52 is in this right-hand position. As above mentioned, both of the valve members 52 and 53 are re-set to their left-hand positions when a fresh operation is required, by causing the control valve 62 to deliver pressure liquid into the connection 67 and thus into the two annular working spaces 57 and 77. This movement of the valve members 52 and 53 to the left also has the action of re-setting the integrating mechanism 37, as will be hereinafter explained, and said integrating mechanism acts to hold both valve members in their re-set positions in readiness for the next operation, which is, of course, brought about by feeding pressure liquid once again through the inlet pipe 63.

The integrating and holding mechanism 37 is also shown in Figure 2 and it comprises a casing 110 containing a valve-holding member in the form of a rack 111, which is in the form of a somewhat rectangular flat plate having a pair of slots 112 and 113 by which the rack member 111 is mounted slidably, in a direction at right angles to the axes of the valves 52, 53, upon a pair of studs 114 and 115 carried by the casing 37; each of the slots has an inclined foot portion indicated at 112a and 113a respectively, acting as deflecting means, so that when the rack member 111 approaches its fully raised position it is deflected towards the right owing to the obliquity of the foot portions 112a and 113a. The rack member 111 is urged downwards by a coiled tension spring 148 connected to the rack member at 116 and anchored to the casing 110 at 117. Along its right-hand edge the rack member 111 is formed with two sets of ratchet teeth indicated at 118 and 119 respectively. The ratchet teeth 118 are engageable by the upper extremity of a flat pawl 120, which is pivoted at 121 to an arm 122, which arm 122 is freely rotatable upon a stud 123 carried by the casing 110; the arm 122 has a depending lug fitted with an adjustable stop screw 124 arranged to engage with a projection 110' on the casing 110, while a bracket 122a is mounted on, and extends upwardly from the arm 122, and is fitted with an adjustable thrust screw 125. The arm 122 is urged downwards by a coiled tension spring 126, while a tension spring 127 connects the lower end 120' of the pawl 120 with the stud 123, thus pressing said pawl towards the edge of the rack member 111. The ratchet teeth 119 are similarly engaged by a pawl 128 pivoted upon a pin 129 fixed to the extremity of an arm 130 and having its top end urged into engagement with the rack member 111 by a coiled tension spring 131 attached to the lower end 128' of the pawl 128. In this case, however, the arm 130 is attached to the spindle 44, which, it will be remembered, is oscillated by rotation of the blower nozzle owing to the action of the cam 41 and tappet 42. Thus for each revolution of the blower nozzle 12 the pawl 128 feeds the rack member 111 upwards through a distance corresponding to one or two of the teeth 119 (depending upon the design of the cam 41 and its associated mechanism). During such upward movement of the rack member 111 the pawl 120 acts as a detent. The arm 130 is provided with a stop screw 132 and is urged downwards by a coiled tension spring 133 having its upper end attached to the rear end of the pin 129. It will be seen that the spindle 40, to which the arm 39 is secured, carries inside the casing 110 a pair of arms 134 and 135; the arm 134 is arranged to engage at its end with an adjustable thrust screw 136 mounted upon a bracket 137 forming part of the rack member 111, while the arm 135 carries a pin 138 (shown in dotted lines) which is adapted to engage with the thrust screw 125 as the spindle 40 reaches the end of its movement in an anti-clockwise direction. Mounted behind the rack member 111 is a rectangular masking plate 139, which is pivoted to the casing 110 about a vertical axis 140, as is shown in Figure 3, the masking plate 139 being urged resiliently towards the rack member 111 by a wire spring indicated at 141. The masking plate 139 is formed with a circular cam projection 142, while the back of the rack member 111 is similarly provided with a circular cam projection 143; these cam projections are disposed in reg-

ister when the rack member 111 is in its lowermost position, as shown in Figure 2, said cam projections 142 and 143 then causing the masking plate 139 to be pushed backwards out of engagement with the pawls 120 and 128. The left-hand edge surface 144 of the rack member 111 is arranged to engage with the stem portions 55 and 76 of the piston valve members 52 and 53 respectively, said rack member thus constituting a stop which holds and positions the valve members 52 and 53 against movement by their corresponding springs 54 and 80. At its lower part the rack member 111 is formed with a step 144a adapted to hold the valve member 53 in its central position.

The operation of the integrating mechanism will now be described with reference to Figures 2 and 3 and to the diagrams shown in Figures 4 to 8 inclusive. Figures 2 and 3 show the positions occupied by the parts towards the commencement of a blowing operation, the nozzle 12 being nearly at the end of its advancing stroke, and the valve members 52 and 53 in their left hand positions. This means that the arm 39 is moving angularly in a clockwise direction, bringing the arm 134 into engagement with the thrust screw 136. The final part of the advancing stroke causes the arm 134 to lift the thrust screw 136 and rack member 111 through a distance corresponding to one of the teeth 118, 119. The selector valve member 53 is then pushed to the right by its spring 89 until the stem 76 engages with the step 144a, as is shown in Figure 4. The piston valve member 53 is then in its central position and feeds the pressure liquid to the rotary motor 22, by means of a groove 85 connecting with the outlet 88, 89 and pipe 103, for turning the blower nozzle 12. At the completion of each revolution the arm 130 is moved upwards, by the action of the cam 41 on the pin 42 causing rotary movement of the spindle 44, and progressively raises the rack member 111 until, after a predetermined number of revolutions have been made, the step 144a has moved upwards beyond the valve stem 76, as indicated in broken lines in Figure 4, thus enabling the spring 80 to move the valve member 53 to its right-hand position shown in Fig. 5. This cuts off the supply of pressure liquid to the rotary motor 22 and transfers it through the connection 91 to the working space 102, so that the reciprocating motor 19 acts to retract the blower nozzle 12. The arm 39 is moved angularly in an anti-clockwise direction, and as the blower nozzle 12 approaches its fully retracted position, the pin 135 on the arm 135 reaches the thrust screw 125, so that the arm 122 is moved upwards and the pawl 120 raises the rack member 111 through a distance corresponding to one of the teeth 118. During this final movement of the rack member 111 the foot portions 112a and 113a are in engagement with the studs 114 and 115, so that the upward movement of the rack member 111 is accompanied by a substantial deflection thereof to the right, to the release position shown in Figure 5; the sideways deflection is sufficient to allow the change-over valve member 52 to shift under the action of the spring 54 to its right-hand position in which it bypasses pressure liquid from the pipe 63 to the pipe 73 leading to the next blower unit in the sequence of operation. During the progressive rising movement of the rack member 111 from the position shown in Figure 2, the masking plate 139 rests against the sides of the pawls 120 and 128, as is shown in Figure 7, but as the spring 141 is relatively light, the masking plate does not impede the action of

said pawls; the masking plate 139 rests against the pawls, of course, owing to the fact that the cam projection 143 has moved out of register with the cam projection 142. The final movement of the rack member 111 to the right, however, as it reaches the top of its stroke causes the pawls 120 and 128 to be carried beyond the masking plate 139, as will be seen in Figure 8, thus enabling the integrating mechanism to reset itself when the valve members 52 and 53 are re-set. Until that time, however, the springs 54 and 80, acting on the rack member 111 through the medium of the valve members, retain said rack member 111 in its elevated position owing to the obliquity of the foot portions 112a and 113a, thus preventing the spring 143 from pulling down the rack member 111. It will be remembered that the valve members 52 and 53 are both in their right-hand positions when the blowing operation has finished, and that they are re-set to their left-hand positions by admitting pressure liquid through the pipe 66 to the working spaces 57 and 77. When the force of the springs 54 and 80 is thus removed from the rack member 111, the return spring 148 is able to pull said member downwards, as is shown in Figure 6, movement to the left taking place at the same time while the studs 114 and 115 are disposed in the foot portions 112a and 113a of the slots. During this movement the pawls 120 and 128 rest against the edge of the masking plate 139 and do not therefore impede the downward movement of the teeth 118, 119. As the rack member 111 reaches its lowermost position the masking plate 139 is deflected owing to the engagement of the cam projections 142, 143, thus enabling the pawls 120 and 128 to re-engage with the rack member 111, as is shown in Figure 3.

In cases where it may be desirable to render any particular blower unit inoperative, a stop pin indicated in broken lines at 145 in Fig. 2 may be provided in order to hold the rack member 111 in its fully raised position; the pin 145 is mounted upon the end of an arm 146, the spindle 147 of which projects through the front of the casing 148 and is provided with an operating handle 147' having two positions, namely a "blower on" position corresponding to the lowered position of the pin 145, as shown in Figure 2, and a "blower off" position in which the pin 145 holds the rack member 111 at the top of its stroke.

Where the blower unit is of the non-retractable type the reciprocating motor 19 is, of course, omitted and the valve device 36 can then be simplified; a convenient arrangement is shown in Figure 9; the valve being indicated at 36a and its integrating mechanism at 37a. The valve 36a comprises a change-over piston valve member 52a, which is identical with that shown in Figure 2, and which is urged towards its right-hand or bypassing position by a coiled compression spring 54. The bore 50 and its ports are also arranged similarly, but in this case the port 71a communicates directly with a motor connection indicated at 39a. This leads to the rotary motor 22 by way of a pipe 103a, while the liquid exhausted by said motor 22 flows back to the reservoir 65 by way of a pipe 104 and the pipe 92a, which latter leads to the drain connection 93a. In the integrating mechanism it is no longer necessary to actuate the arm 122, so that the pawl 120 carried thereby merely acts as a detent to prevent downward movement of

the rack member 111 while the lower pawl 128 is being actuated due to rotation of the cam 41 (Figure 1) and spindle 44. Re-setting of the valve member 52a is carried out as before by admitting pressure liquid to the annular working space 57 by way of the pipe 66, thus forcing the valve member 52a to the left against the action of the spring 54 and enabling the return spring 148 to pull the rack member 111 downwards to the position shown in Figure 9, the pawls 120 and 128 resting against the edge of the masking plate 139 until this position is assumed similar to the position shown in Figure 6. When the pressure liquid is cut off from the re-setting pipe line 66, the rack member 111 retains the valve member 52a in its left-hand position, to start the next blowing operation when the control valve 62 is actuated to feed pressure liquid from the pump 60 through the pipe 63 to the enlargement 58. The liquid then flows through the port 71a and connection 89a to the rotary motor 22, thus driving the blower nozzle 12 and causing the arm 130 to be oscillated so that the pawl 128 feeds the rack member 111 progressively upwards. At the revolution before the last the foot portions 112a and 113a reach the studs 114, 115, and therefore when the rack member 111 is further raised during the last revolution, said rack member moves to the right owing to the obliquity of the said foot portions, thus permitting the spring 54 to move the valve member 52 to its right-hand or bypass position. This cuts off the supply of pressure liquid to the rotary motor 22 and diverts it through the pipe 73 to the next blower in the sequence. The integrating mechanism shown in Figure 9 resets itself automatically when the valve member 52 is being re-set, the action being the same as in the preceding example, with the masking plate 139 holding the pawls 120 and 128 away from the teeth 118, 119, until the rack member 111 reaches its lowermost position, at which point the said masking plate 139 is deflected by the projections 142, 143.

An alternative form of valve and integrating mechanism suitable for a blower head of the non-retractable type is shown in Figures 10 and 11, the valve being indicated at 36b and the integrating mechanism at 37b. Disposed within the bore 50 is a piston valve member 52b, which is formed at its right-hand end with a stem 154 screw-threaded into a yoke member 155 constituting part of the integrating mechanism 37b. The right-hand part 155a of the yoke member 155 is formed with a spigot 156 serving as a guide for a coiled compression spring 54b, which latter abuts against a cap 157 and is arranged to urge the yoke member 155 and the piston valve member 52b towards the left. The valve 36b is of the same general construction as the change-over valves described above, the valve member 52b having an annular groove 69b which is in permanent communication with the enlargement 58 of the bore 50, said enlargement being fed with pressure liquid through a pipe 63 by means of a pump 60 and control valve 62. When the valve member 52b is in its set position, as shown in Figure 10, the groove 69b enables the pressure liquid to flow through the connection 89b and pipe 103 to the rotary hydraulic motor 22. On the other hand when the valve member 52b is in its left-hand position, the enlargement 58 then communicates with a groove 68b arranged to conduct the pressure liquid to an outlet connection 72b and a pipe 73 leading to the pres-

sure inlet next in the sequence; at the same time the groove 69b connects the motor port 88b with a port 158 leading to the drain connection 93b and thence to the reservoir 65 by way of the pipe 92. To re-set the valve member 52b the control valve 62 is operated to deliver pressure liquid through the pipe 66 leading to the re-setting connection 67 and a working space 57b at the left-hand end of the bore 50. The pressure liquid then acts upon the end of the piston valve member 52b and urges it towards the right against the force exerted by the coiled compression spring 54b.

The integrating mechanism, which is arranged to hold the valve member 52b in the re-set position, comprises a latch bar 159 of rectangular cross-section slidably fitting between the sides 160 and 161 of the yoke member 155 and supported by a tubular guide 162 extending from the casing 110b downwards within a bore 164 formed in the latch bar 159. The tubular guide 162 and the bore 164 contain a coiled compression spring 165, which acts to urge the latch bar 159 downwards, while a pad 166 rigidly secured to the casing 110b by bolts 167 serves to support the latch bar 159 against movement towards the left on account of the force of the spring 54b. At its lower part the latch bar 159 is reduced in width to form a step 168, the arrangement being such that when the latch bar is in its lowered position, as shown in Figure 10, it effectively holds the yoke member 155 in its right-hand position, whereas when the latch bar 159 rises to a position where its surface 169 is disposed above the upper surface 170 of the part 155a, then the yoke member 155 and the valve member 52b can both move to their left-hand positions under the influence of the spring 54b. In order to bring about this rising movement a rocker 130b mounted upon the spindle 44b is urged in an anti-clockwise direction by a spring 133b and is fitted with a driving pawl 128b, which latter is urged towards the latch bar 159 by a spring (not shown). At its upper part the latch bar 159 is formed with a series of wide ratchet teeth 119b, which are engaged by the driving pawl 128b and also by a detent pawl 120b, the latter being pivoted to the casing 110b at 171 and also being urged towards the latch bar 159 by a spring (not shown). The pawls 120b and 128b are sufficiently wide and are so mounted that they extend beyond the edges of the latch bar 159, as is shown in Figure 11, the protruding parts being disposed in line with projections 172 and 173 formed upon the sides 160 and 161 of the yoke member 155; the projections 172 and 173 are, however, normally out of engagement with the pawls, even when the yoke member 155 is in its re-set position, shown in Figures 10 and 11.

At its lower part the casing 110b is provided with a spindle 147b carrying an arm 146b, the free end of which is in engagement with the bottom of the latch bar 159, so that angular movement of the spindle 147b in a clockwise direction acts to raise the latch bar 159. The spindle 147b projects through the front of the casing 110 and is provided with an angularly movable handle (not shown) adapted to be positively located in any one of a predetermined number of angular positions within its range, each position corresponding to a predetermined number of revolutions of the blower nozzle.

When the device is in its re-set position, as shown, and pressure liquid is fed by the control valve 62 to the pressure inlet connection 63 to

75

drive the rotary motor 22, the spindle 44b is oscillated by the cam 41 (as described with reference to Figure 1) once for each revolution, the clockwise angular movement of the rocker 130b actuating the pawl 128b so that it lifts the latch bar 159 by an amount corresponding to one of the teeth 119b. During the return movement of the rocker 130b the latch bar 159 is sustained by the detent 120b. In this way, as the rotation of the blower nozzle 12 proceeds, the latch bar 159 reaches the position where the surface 169 rises beyond the surface 170, thus allowing the spring 54b to move the yoke member 155 to the left, the part 155a engaging the step 168 and the valve member 52b being moved to its by-pass position. This of course diverts the pressure liquid to the next blower in the sequence and the blower nozzle 12 comes to a standstill. The number of revolutions which are necessary to bring the latch bar 159 to its fully raised position depend, of course, upon its initial height and this can readily be adjusted by means of the arm 146b; if necessary the latch bar can be held in its fully raised position by said arm, thus rendering the blower inoperative by preventing the valve member 52b from remaining in its right-hand position when the device is re-set.

To re-set the device, pressure liquid is admitted to the working space 57b as described above, thus moving the valve member 52b and yoke member 155 to the right against the force of the spring 54b. These parts move beyond the position shown in Figure 1, thus enabling the projections 172 and 173 to bear against the pawl 128b and detent 120b and move them out of engagement with the teeth 119b. The latch bar 159 is therefore released and is moved downwards by the spring 165, until its lower end abuts against the arm 146b which forms a stop. When the liquid pressure is cut off from the working space 57b, the valve member 52b and the yoke member 155 are pressed back slightly by the spring 54b until the part 155a bears against the latch bar 159, this movement serving to disengage the projections 172, 173 from the detent 120b and pawl 128b, so that the latter can raise the latch bar 159 when the motor 22 is next operated.

It is to be observed that the arrangements which have been described are given merely by way of example and that various modifications may be made in the construction and arrangement of the parts; also that the invention is not limited to soot blower systems, as the hydraulic motor units can obviously be employed for other purposes.

What I claim is:

1. For a soot-blower system, a hydraulically-operated nozzle-actuating unit, comprising nozzle rotating mechanism, a hydraulic motor driving said mechanism, a change-over valve, a by-pass connection therefrom, the change-over valve receiving pressure liquid from the supply and in one position feeding it to the motor and in another position delivering it to the by-pass connection leaving the hydraulic motor inoperative, a spring urging the change-over valve at all times to its by-passing position, valve operating means for moving the change-over valve against the spring force to its feed position, and a holding device for retaining the change-over valve in said feed position, said holding device comprising a holding member slideable across the direction of valve movement and formed with a surface which controls the change-over valve, and integrating mechanism which connects the nozzle with the

holding member and moves said holding member at each revolution of the nozzle unit, until a position is reached where the holding member releases the change-over valve and allows the spring to move the change-over valve to its by-pass position.

2. For a soot-blower system, a hydraulically-operated nozzle-actuating unit, comprising nozzle rotating mechanism, a hydraulic motor driving said mechanism, a change-over valve, a by-pass connection therefrom, the change-over valve receiving pressure liquid from the supply and in one position feeding it to the motor and in another position delivering it to the by-pass connection leaving the hydraulic motor inoperative, a spring urging the change-over valve at all times to its by-passing position, valve operating means for moving the change-over valve against the spring force to its feed position, and a holding device for retaining the change-over valve in said feed position, said holding device comprising a holding member slideable across the direction of valve movement and formed with a surface which controls the change-over valve, ratchet teeth formed on the holding member, a pawl oscillated by the rotation of the blower nozzle and engaging said ratchet teeth, thereby progressively moving the holding member towards a release position in which said holding member is disposed free of the change-over valve to allow the spring to move the change-over valve to its by-pass position.

3. A nozzle-actuating unit according to claim 2, including pin and slot mechanism supporting the holding member, the slot having a terminal portion disposed obliquely so that after reaching a predetermined position the holding member moves obliquely in a direction away from the change-over valve, thereby allowing the spring to move the change-over valve to its by-pass position.

4. For a soot-blower system, a hydraulically-operated nozzle-actuating unit, comprising nozzle rotating mechanism, a hydraulic motor driving said mechanism, a change-over valve, a by-pass connection therefrom, the change-over valve receiving pressure liquid from the supply and in one position feeding it to the motor and in another position delivering it to the by-pass connection leaving the hydraulic motor inoperative, a spring urging the change-over valve at all times towards its by-passing position, valve re-setting means for moving the by-pass valve against the spring force to its feed position, holding means which retain said valve member in said feed position and are actuated by the motor to release the valve when the motor has moved a predetermined amount, thus allowing the spring means to move the change-over valve to its by-passing position, and integrating mechanism, operated at each revolution of the nozzle to control the holding means and cause the change-over valve to be released when the nozzle has made a predetermined number of revolutions, the integrating mechanism and holding means including a holding member comprising a rack plate formed with slots extending parallel with an edge by which the change-over valve is held, studs engaging said slots to guide the rack plate, ratchet teeth carried by said plate, a pawl engaging said teeth and oscillated by rotation of the nozzle, and deflecting means whereby the final movement of the plate takes place laterally with respect to said edge and frees the change-over valve.

5. A nozzle-actuating unit according to claim

13

4, wherein the slots have foot portions inclined with respect to said edge and arranged to deflect the rack plate sideways as the foot portions of the slots engage the studs.

6. A nozzle-actuating unit according to claim 1, having spring means urging the holding member toward its normal position, and having in the change-over valve, a liquid pressure working chamber, to which pressure liquid is admitted to urge the change-over valve back to its normal position, thereby freeing the holding member and allowing the spring means to return the holding member back to its normal position.

7. A nozzle-actuating unit according to claim 4, wherein the integrating mechanism comprises a masking plate which is urged laterally against the pawl and holds the latter out of engagement with the ratchet teeth while the rack plate is being re-set, and a cam device which moves the masking plate away from the pawl as the rack plate reaches its re-set position.

8. A nozzle-actuating unit according to claim 4, wherein the integrating mechanism comprises a masking plate, a spring urging said masking plate laterally against the pawl and thus holding the pawl out of engagement with the ratchet teeth while the rack plate is being re-set, and a cam device comprising a pair of cam projections carried respectively by the masking plate and the rack plate, which cam projections come into register as the rack plate reaches its re-set position, and thus move the masking plate away from the pawl.

9. A nozzle-actuating unit according to claim 4, wherein the integrating mechanism comprises a masking plate, a spring urging said masking plate laterally against the pawl and thus holding the pawl out of engagement with the ratchet teeth while the rack plate is being re-set, a cam device which moves the masking plate away from the pawl as the rack plate reaches its re-set position, and a spring urging the rack plate to its re-set position.

10. A nozzle-actuating unit according to claim 4, wherein a first pawl engages the rack plate and is oscillated by rotation of the blower nozzle, and a second pawl, actuated by axial advance and retraction of the blower nozzle, also engages said rack plate, the first and second pawls both advancing the rack plate in the same direction.

11. A nozzle-actuating unit according to claim 4, having a selector valve which controls advancing and retracting movements of the blower nozzle as well as the rotation thereof, and is positioned by the rack plate.

12. A nozzle-actuating unit according to claim 4, having a selector valve which controls advancing and retracting movements of the blower nozzle as well as the rotation thereof, and is positioned by the rack plate, and a step formed on said rack plate for locating the selector valve in an intermediate position, in which it feeds with pressure liquid the motor which rotates the blower nozzle.

13. A nozzle-actuating unit according to claim 65

14

4, said hydraulic motor being a rotary motor for rotating the blower nozzle, said unit including also a selector valve which controls advancing and retracting movements of the blower nozzle

5 as well as the rotation thereof, and is positioned by the rack plate, a step in the rack plate for locating the selector valve in an intermediate position in which said selector valve feeds the pressure liquid to the motor serving to rotate the 10 blower nozzle, a spring urging the selector valve to a position in which it brings about retraction of the blower nozzle, and liquid pressure means which re-set the selector valve to its "nozzle advancing" position.

15 14. A nozzle-actuating unit according to claim 1, having a yoke member pressed by the spring of the change-over valve against the side of the holding member, said holding member being slideable relatively to the yoke member, and a step being formed in the holding member to enable the yoke member and the valve to move to the bypassing position when the holding member reaches a predetermined position.

16 15. A nozzle-actuating unit according to claim 1, having a yoke member pressed by the spring of the change-over valve against the side of the holding member, said holding member being slideable relatively to the yoke member, a step being formed in the holding member to enable the yoke member and the valve to move to the bypassing position when the holding member reaches a predetermined position, said unit also including ratchet and pawl mechanism which moves the holding member during rotation of the blower 30 nozzle, the pawl being disengaged from the ratchet teeth by the yoke member when the latter is moved against the spring during the re-setting of the change-over valve.

17 16. A nozzle-actuating unit according to claim 1, wherein a yoke member is pressed by the spring of the change-over valve against the side of the holding member, the latter being slideable relatively to the yoke member, a step being formed in the holding member to enable the yoke member and the valve to move from a held position to the bypassing position when the holding member reaches a predetermined position, and wherein a tubular stem slidably carries the holding member, a coiled compression spring disposed within 45 the tubular stem urging the holding member towards its holding position.

EDWARD CLAUDE SHAKESPEARE
CLENCH.
